ABSTRACT OF THE DISCLOSURE

The disclosure describes a preferred embodiment of my invention concerning a vacuum switch comprising a housing having an annular metallic or conductive section 10 and an insulating or nonconductive section 11. An inwardly directed baffle structure 15 is positioned substantially across the housing adjacent to the joinder of section 11 and 12. The nonconductive section 11 has an annular wall 16 formed of glass or ceramic material. The switch has a stationary contact assembly 21 and an opposed movable contact assembly 22 that are mounted to the end walls 13 and 17 respectively. The stationary contact assembly 21 has a terminal rod 23 with an axial cavity 37 formed therein offset from the longitudinal axis of the switch. The movable contact assembly 22 has a terminal rod 27 aligned and opposed to rod 23. Rod 27 has an axial cavity 38 formed therein that is offset from the longitudinal axis and diametrically opposite cavity 37. Contacts 24 and 29 are mounted on the adjacent ends of the rods 23 and 27 respectively. A passageway 42 is formed in rod 23 communicating with the cavity 37 and the exterior of the rod. A post 40 of gettering material is positioned in the cavity 37.

My invention relates to vacuum switches and more particularly to vacuum switches that are capable of being used as circuit breakers carrying high current loads.

One of the objects of my invention is to provide a new vacuum switch that is efficient in operation, simple in construction and economical to manufacture.

An additional object of my invention is to provide a new vacuum switch that has increased longevity and reliability.

A further object of my invention is to provide a vacuum switch that is capable of operating with increased current ratings.

An additional object of my invention is to provide a novel vacuum switch structure that minimizes the depositing of metallic material on the insulator.

A further object of my invention is to provide a vacuum switch for use as a circuit breaker in which the movable portion of the switch has a relatively small mass to enable the switch to operate faster.

An additional object of my invention is to provide a vacuum switch that is capable of shifting the location of the arc across the switch contacts in order to reduce the erosion of the contacts.

A further object of my invention is to provide a novel vacuum switch structure for shielding the insulator from the metallic vapors generated by the arcing.

An additional object of my invention is to provide a novel application of gettering material within the switch vacuum chamber to insure the continuance of high vacuum (throughout the life of the contacts).

Other objects and advantages of the invention will become apparent by reference to the following detailed description and the accompanying drawings illustrating a preferred and other embodiments thereof, in which:

FIG. 1 is a cross sectional view of a vacuum switch

2

showing the principal elements of a preferred embodiment of my invention;

FIG. 2 is a cross sectional view of a vacuum switch showing certain modification of the preferred embodiment;

FIG. 3 is a cross sectional view of a vacuum switch showing certain modification of the preferred embodiment in which a baffle shield is supported by the insulator spaced from the conductive elements of the switch; and

FIG. 4 is an artistic perspective view showing the electrical contacts of the vacuum switch emphasizing the magnetic field pattern around the contact elements.

FIRST EMBODIMENT OF VACUUM SWITCH

FIGURE 1 illustrates in cross section the details of a first switch embodiment incorporating the basic elements of my invention. The electrical contact assemblies are enclosed within a sealed housing comprising a conductive annular section or wall made from metallic material generally designated by the numeral 10 and nonconductive or insulating section or wall generally designated by the numeral 11. An arc chamber 12, wherein arcing is confined during opening of the contact assemblies, includes the conductive annular section 10 sealed at one axial end to an end metallic wall 13. The remaining end of section 10 is sealed at 14 to the adjacent open end of the nonconductive section 11. Any conventional seal might be used between the joined conductive members or between the conductive members and the nonconductive members. As illustrated, the metal to metal seals would most likely be brazed, and the metal to insulation seals would be formed by embedding metal connecting strips in the glass insulator structure as it is being formed.

The arc chamber 12, whose interior is open to the insulating section 11, is substantially enclosed by an inwardly directed baffle structure 15 to the joinder of the insulating section 11 and arc chamber 12. In FIGURE 1 the baffle 15 is shown as a metallic wall inwardly directed from the open axial end of the wall 12. It is the area enclosed by the walls 10, 13 and 15 which is generally referred to herein as the "arc chamber."

The insulating section 11, formed adjacent to the arc chamber 12, comprises an annular wall 16 formed of glass or ceramic material sealed respectively to the arc chamber 12 at 14 to a second end wall 17 at 18. The wall 17 is axially spaced from wall 13, and the area lying between these end walls defines the axial limits of the vacuumized enclosure. Air is evacuated through a tube 20 extending through an aperture formed in end wall 17. The tube 20 is pinched off to seal the evacuated enclosure.

The electrical contact assemblies used in the switch shown in FIGURE 1 are generally designated by the numerals 21 and 22. The contact assembly 21 is stationary while the contact assembly 22 is movable between a first position in abutment with contact assembly 21 and a second position displaced axially therefrom.

The stationary contact assembly 21 includes a post or rod 23 fixed to the end wall 17. The rod 23 protrudes outwardly through wall 17 and its outer end comprises a first electrical terminal for the switch components. A radially enlarged contact 24 having a plane contact surface 25 is affixed to the inner end of rod 23. Rod 23 also supports an annular baffle 26 located outwardly adjacent to baffle 15 and the joinder of sections 10 and 11; the baffles 15 and 26 overlapping one another so as to provide a circuitous route to minimize escape of metallic vapor from within the arc chamber 12.

The movable contact assembly 22 includes a supporting post or rod 27 slidably guided by end wall 13 within an inwardly projecting bearing 28 and serves as the second electrical terminal for the switch. Rod 27 is aligned

axially with rod 23 and is carried by bearing 28 for sliding movement parallel to the longitudinal axis of the switch. At its inner end it carries a radially enlarged contact 29 having a plane contact surface 30 complementary to the contact surface 25 previously described. The integrity of the vacuum within the enclosure is maintained by a flexible vacuum tight sealing means or bellows 31 having one end sealed at 32 to the rod 27 and having its remaining end sealed at 33 to the end wall 13. The bellows 31 is partially enclosed within a protective annular cover 34 fixed to rod 27 and movable in unison with it.

The switch is adapted to be mounted in a fixed position by means of three equally spaced lugs 35 which protrude outwardly from end wall 13 and which are centered about the axis of posts 23 and 27. The outer end of rod 27, which protrudes outwardly from end wall 13, is threaded at 36 to provide a mechanical connection to a suitable device (not shown) for opening or closing the contact assemblies as might be necessary in the application to which the switch is directed.

The contacts 24 and 29 are preferably fabricated of tungsten and copper, utilizing available compositions wherein the tungsten is porous, having its voids filled with copper. Such a composition is obtainable with extreme metal purity and essentially no gaseous content.

It should be noted that the movable contact assembly 22 as shown in FIGURE 1 has a relatively small mass as compared to circuit breakers presently available. The small mass permits faster operation of the switch and allows the moving elements to be mechanically shifted by a relatively smaller force being applied by the mechanism that moves post 27.

The arc chamber 12 confines any arc momentarily directed across the contacts 24 and 29 as they are opened. Metallic vapors produced by such an arc will condense or be deposited on the surfaces of the members 10, 13, 15 and 26 so that no substantial amount of such products will be deposited on the inside surface of the insulating wall 16. Such an arrangement increases the longevity and reliability of the switch.

The design of rods 23 and 27 as shown in FIGURE 1 incorporates two additional features of importance of my basic invention. The first of these is provision for a moving magnetic field to prevent concentration of an arc across contacts 24 and 29 in any one particular location. To accomplish this, the inner end of rod 23 is provided with an axial cavity 37. The central axis of cavity 37 is radially offset from the longitudinal axis of the rod 23, thereby making the cavity 37 eccentric relative to the rod 23. As shown, rod 27 is provided with a similar eccentric cavity 38. Cavity 38 is illustrated as being offset diametrically opposite to cavity 37. In general, either one rod, or both (as illustrated), may be so formed to shift the center of the electrically conductive mass of one or both rods adjacent to their respective inner ends.

The shift in the center of the electrically conductive mass of one or both posts results in a shift in the magnetic field which will be developed about the rods and contacts as electrical current passes through them. This feature will be discussed further in detail below, and for the present it is sufficient to state that the shifting magnetic field will result in continuous movement of the location at which an arc between the two contacts will be directed relative to their respective contact faces.

An additional feature is illustrated on rod 23. This is the inclusion of a post 40 anchored to the interior of contact 24 and extending within the cavity 37. Post 40 is preferably made of refractory metal such as molybdenum or tantalum. A gettering material, such as "Ceralloy" (manufactured by Ronson Metals Corp.) is sintered to post 40 to absorb gases in its surrounding environment. It is used to remove from the interior of the enclosure any gaseous molecules which might be produced during operation of the switch components. The interior of cavity

37 is in open communication with the interior of the arc chamber 12 by means of an intersecting passageway 42 formed through rod 23. The side walls of the gettering material on post 40 are spaced from the side walls of cavity 37 so as to provide maximum surface exposure of post 40. The location of the gettering assembly in cavity 37 serves to protect this active material from damage and contamination by metal vapors during operation (or arcing).

Since a gettering material as described absorbs gas more actively as its temperature is increased, the removal of gas from the environment surrounding post 40 will be proportional to the severity of the electrical load handled by the switch components. The supporting post 40 is preferably a refractory metal having characteristics capable of high temperature vacuum outgassing prior to application of gettering material. Preferably this material should be molybdenum or tantalum, either of which introduces a slight delay in the time of maximum operation of the gettering material, due to their thermal conductivity characteristics. The action of the gettering material will therefore be most effective at the time slightly after the opening of the contact assemblies, so that gaseous materials are most effectively removed after extinguishing of the arc, when such materials will be most prominent within the arc chamber 12. The action of the gettering material serves to continually maintain the quality of the vacuum within the enclosure and thereby insures longer life for the switch than is possible in conventional vacuum switches without such provision.

The construction of the apparatus shown in FIGURE 1 permits the switch to be applied as a circuit breaker and recloser switch with desirable switching characteristics particularly required in the design of larger, higher rated units. This structural relationship increases the longevity of the switch and reduces the normally high transient voltages which arise during the circuit breaking operation in a vacuum environment.

The size and power capability of the switch can be extended by enlarging the components making up the arc chamber 12 and insulating section 11. The metal components of the arc chamber 12 may be enlarged both in diameter and depth in order to accommodate larger electrical parts and to thereby increase its current handling ability. The insulator section 11 might also be increased in wall thickness, diameter or length as required for higher voltage stand off. Larger units would probably be oriented vertically with the wall 13 serving as the lower supporting base member. The combination of the metal arc chamber and the insulating section provides greater versatility and capacity in this unit than is possible in prior vacuum switches fully enclosed within a glass or insulating envelope.

SECOND EMBODIMENT OF THE APPARATUS

In FIGURE 2 is illustrated a modified second embodiment of the basic switch construction illustrated in FIGURE 1. The switch shown in FIGURE 2 operates sequentially in a two step operation as opposed to the instantaneous opening of the solid contacts illustrated in FIGURE 1. In the case of the switch shown in FIGURE 2, initial movement of the movable contact opens only a portion of the contact area and increases the effective electrical resistance of the movable contact assembly prior to complete opening thereof.

In the case of a vacuum switch used for making or breaking circuits having high electrical loads, the switch shown in FIGURE 2 has advantages over the simple two contact switch apparatus. Rapid interruption of current often causes the generation of transient voltages of great magnitude in equipment connected in the circuit. These high voltage transients can serious damage such equipment. The apparatus shown in FIGURE 2 is capable of preventing such transient voltages from becoming of great magnitude by providing improved control of the

rate of disconnection of the circuit. Specifically, this apparatus provides means for reducing the current in the circuit by a substantial degree prior to complete opening of the circuit.

As seen in FIGURE 2, the basic features of the switch assembly are similar to that shown in FIGURE 1. The enclosure within which the switch is housed includes an arc chamber 42 and an insulating section 43. The arc chamber 42 is formed by a bell-shaped annular wall 44 leading inwardly to a wall section 45 that is of a reduced diameter at its inner end. The reduced section 45 is joined to a cylindrical shell 46 of insulating material. The shell 46 is sealed to both the wall section 45 and to an end wall 47. The metal wall member 44, 45 and 47 are preferably made of an alloy having proper thermal coefficient of expansion characteristics to match the insulating shell 46. In one practical form of the apparatus, shell 46 is made of calcium aluminosilicate glass, such as that sold as "Corning's Code 1723." A matching sealing metal such as low carbon molybdenum is used for high temperature characteristics, and greater ductility, or a lower temperature hard glass may be used with an alloy having matching thermal expansion characteristics.

In this form of the invention, the stationary contact is mounted on the shorter of the two rods, the movable contact being in two parts and requiring the longer bearing support. The stationary contact 48 has a first contact surface 49a and a second contact surface 49b. The movable contact includes an outer annular contact 50 and an inner circular contact 51. The facing surface of contact 50 is complementary to the contact surfaces 49b and the facing surface of contact 51 is complementary with the contact surface 49a.

The stationary contact 48 is supported by the end wall of the bell-shaped wall section 44 on a copper rod 52. Rod 52 includes an axial cavity 53 within which is mounted a post 54 having flashless gettering material sintered to it in the manner previously described. The post 54 is preferably a heat conductive post of tungsten or molybdenum.

The cavity 53 is intersected by a radial passageway 55 formed through the rod 52 so as to place cavity 53 in open communication with the interior of arc chamber 42. In this manner, gaseous particles within arc chamber 42 can contact the gettering material on post 54 and thereby removed.

Rod 52 is provided with a continuing aperture 56 in communication with cavity 53, leading to a copper tube 57 through which air is removed from the interior of the enclosure, the tube 57 being pinched to a closed position after evacuation of the enclosure.

The stationary contact 48 and the inner movable contact 51 are preferably made of porous tungsten with a filling of copper in the pores or voids of the material. The outer movable contact 50 is preferably made of similar material having relatively lower electrical conductivity so as to furnish greater resistance to the flow of current that is furnished by the material used in contact 48 and contact section 51.

The inner contact 51 is fixed to the inner end of an inner rod 58 aligned coaxially with contact 48. The rod 58 is slidably received through a hollow outer rod 60 by means of bushings 61 and 62 at its respective outer and inner ends. Rod 60 is in turn slidably supported by a bearing 63 fixed to the end wall 47 in a sealed relationship. The movable connection for rod 60 is sealed by a flexible stainless steel bellows 64 sealed at one end to bearings 63 and to its remaining end to a disc 65 fixed to rod 60. The connection between rod 60 and rod 58 is sealed by a similar flexible bellows 66 sealed at one end to rod 60 and at its remaining end to rod 58. In this way, the integrity of the vacuum within the enclosure is maintained despite the relative movement afforded between rods 58 and 60.

The outer end of rod 58 is provided with a threaded aperture 67 to which a suitable device for moving the contacts can be mechanically connected. The rod 58 in-

cludes an annular shoulder 68 adjacent its outer end adapted to move axially between an outer shoulder 70 and an inner shoulder 71 fixed to the hollow rod 60. It can thus be seen that the movement of rod 58 to the right in FIGURE 2 will first leave rod 60 and contact section 50 unmoved. After the inner rod 58 and contact section 51 have moved the distance permitted prior to contact of shoulder 68 with shoulder 70, continued movement of rod 58 will result in movement of rod 60 and contact 50 in unison with it, thus providing a lost motion connection. Closing of the contacts will occur in precisely the opposite sequence. First, both contact 50 and 51 will move simultaneously until the contact section 50 abuts contact 48. Continued movement of rod 58 will finally bring the contact 51 also in abutment with contact 48. This sequence of operation is insured by proper design of the external operating mechanism (not shown).

This two step operation, when coupled with a proper choice of electrical conductive properties for the contact members, results in a momentary increase in the electrical resistance through the switch immediately prior to complete opening of the contacts. Assuming that the electrical conductivity of the outer movable contact 50 is less than that of the inner movable contact 51, the resistance of the switch will be increased after initial opening to the contact 51. This will reduce the magnitude of current and voltage that the remaining contact 50 must operate against upon opening or separating from the stationary contact 48. This increase in effective resistance of the contacts results in the protection of the higher conductive contact 51 from erosion by arcing. Furthermore, the magnitude of recovery voltages and the time during which the voltages shall rise in equipment in a power circuit including this switch following interruption of current will be reduced due to the increased resistance of the switch introduced during its operation.

In this form of the apparatus, the arc chamber 42 is physically separated from the insulating section 43 by a radial baffle 72 extending outwardly from the post 60. The barrier 72 is in outward juxtaposition with the reduced wall section 45 so as to substantially enclose the arc chamber 42 when the contacts are in their closed positions. Barrier 72 serves to protect the insulating section 43 of the enclosure from metallic vapors that might be released during arcing caused by opening of the contacts.

MOVEMENT OF AN ARC IN A VACUUM CIRCUIT BREAKER

As discussed above, it is advisable in a vacuum circuit breaker or switch to prevent any arc or arc spots from remaining in the same location on two contacts since such a stationary condition will cause excess local heating and vaporization of the contacts. The result of such action is erosion of the contact surfaces and deterioration of the vacuum purity. In the operation of an electrical circuit interrupter in a power circuit, an arc may occur resulting in continued current flow between the contacts of the device as the contacts open and move apart. Such an arc normally originates from and continues to flow between cathode and anode spots on the two contacts. With a conventional contact, these arc spots are normally confined to a small part of the available contact area and the power concentration at such small areas generates extremely high local temperatures. Resulting in vaporization due to the high temperatures creates a plasma which in turn supports the arc. To reduce these temperatures, it is advisable to prevent the arc spots from dwelling at any one location on the contacts.

In FIGURE 4 is illustrated the general structure by which the cathode and anode spots of such an arc can be maintained in motion. The rod 80 which carries the stationary contact 82 is shown with an eccentric axial cavity 81 formed through it adjacent to the contact 82. The movable rod 83 has a similar cavity 84 adjacent to the movable contact 85. The heavy current that flows through

the switch during fault conditions causes an unsymmetrical electromagnetic field to exist in the region about contacts 82 and 85 when these contacts are carrying electrical current. A similar phenomena could be obtained by the use of any number of different physical configurations of the conductors which would cause it to be asymmetrical, or by placing a material of high magnetic permeability about the conductor in an asymmetrical manner.

The magnetic force fields generated about rods 80 and 82 by the current flowing through them are asymmetrical with respect to the central longitudinal axis of rods 80 and 83. In addition, since the cavities 81 and 84 are diametrically opposed, the fields are further disoriented with respect to the general axis of the arc path between contacts 82 and 85. This distorted magnetic force field, illustrated statically in FIGURE 4 and designated by the numeral 86, reacts with the fields of the ions and electrons in motion in the arc plasma during opening of the contact to cause a displacement of the arc from its normal path, resulting in movement of the arc spots on the surfaces of contacts 82 and 85. Because of the dynamic nature of the arc and the varying nature of the power line current flowing through the switch, plus oscillatory currents in most interrupting operations, the asymmetrical magnetic force field will also be dynamic and constantly changing. This movement will maintain the arc spots in continuous movement until the arc is finally extinguished. The movement will be random and will prevent the arc from concentrating on any particular area of the contact surfaces.

To make best use of the displaced magnetic fields, the conductors should be constructed in a manner so as to place the asymmetry in proximity to the switch contacts. Furthermore, the displaced electrical axis (and consequently the displaced magnetic fields) of the two conductors that support the contacts may be arranged so that they are not in coaxial alignment. This displacement (FIGURE 4) provides a twisting toroidal magnetic field in the space about the two contacts. The magnetic field about the rods 80 and 83 is shown in FIGURE 4 as it would exist under static conditions with the contacts 82 and 85 closed and with direct current flowing through the electrodes. It is to be noted that the electromagnetic lines of force 86 are both axially displaced and angularly distorted in the area adjacent to the contacts. Phase changes would cause rotation of the twisted magnetic fields and amplitude changes would cause variation in its strength. As the contacts opened, this dynamic picture would be increasingly complex, and would be constantly changing in an irregular pattern.

An electrical arc in such a moving magnetic environment would be forced to move and would be prevented from concentrating on an initial or favorable hot cathode spot. This is true because of the conductive nature of the gas that is present even in high vacuum environments, to support any electrical arc. Such a gas is highly ionized and will encounter forces which tend to move it in a direction normal to the moving magnetic field. The arc supported by these particles will be moved as a result.

The general structure for moving the arc between the contacts is incorporated directly in the switch shown in FIGURE 1 as described above and can be readily applied to any modification of this general switch structure, such as that shown in FIGURES 2 and 3. The application of this structure is not limited to any physical configuration of the cavities, rods or contacts, and can apply to a wide variation of structural requirements relating to many switch applications.

THIRD SWITCH MODIFICATION

In FIGURES 1 and 2 the two chambered structure is shown with an inwardly directed wall supported by the metal wall section of the arc chamber adjacent to its inner end. In FIGURE 3 is illustrated a slight modification of the switch structure shown in FIGURE 1. In this in-

stance, the structure relating to the contact assemblies 21 and 22 is unchanged and similar reference numerals are used to designate the parts as shown. The cylindrical wall 10' is shown in sealed contact with the inner end of an insulating wall section 16'. The wall section 16' is sealed to an end wall 17' and the metal wall section 10' is sealed to an end wall 13'.

In this instance, a metallic shield 90 is shown mounted on the insulating section 16'. The baffle shield 90 includes a cylindrical wall that extends to an area adjacent to the end wall 13'. The shield 90 is supported by an interior annular groove 91 formed about the insulating section 16', the shield 90 including a cooperating exterior shoulder or projection 92. At its inner end, shield 90 extends inwardly at 93 to a location adjacent to the contact posts extending through the insulating section 16'.

This shield 90 serves the same basic purpose as the inwardly directed wall sections and baffles mounted on the posts and shown in FIGURES 1 and 2. That is, it mechanically deflects or collects particles emitted in the arc chamber during opening of the contacts. This prevents collection of metallic particles on the interior of the insulating chamber 16'. However, the electrical properties of shield 90 are different from those of the baffles and wall sections previously described. The shield 90 will be "floating" on potential in that it is supported only by the insulating part of the vacuum enclosure. The advantage of this floating potential is that during operation of the switch it is not fixed in potential equal to either one electrode or the other. During operation of the moving contacts in interrupting the current of an electric circuit, the floating baffle will tend to assume a potential determined by the nature of the arc vapors that strike it. This will vary from one operation to another being principally dependent upon the amplitude of the current being interrupted.

When the switch is open and the electric connections are energized, the shield 90 will be either at approximately one quarter or three quarters of the line potential, depending upon the manner in which the device is connected in the line. When the switch is closed with normal line current flowing through it, there will be no significant difference in potential between the shield 90 and the switch contacts. The manner of mounting the shield 90 on the inside surface of the insulating section 16' takes full advantage of the high resistance to voltage breakdown afforded by the vacuum environment within the enclosure. The shield does not extend through the insulator to the exterior of the enclosure where atmospheric pressure conditions might allow arcing or high voltage tracking to occur. The potential at the shield 90 is structurally insulated from the exterior of the enclosure. Obviously, this structure could be equally well applied to the apparatus shown in the second embodiment of the switch (FIGURE 2).

Many combinations of the specific features set out above and many obvious substitutions of equivalent structures will readily present themselves to one skilled in the art. Therefore, only the following claims are intended to define my invention.

Having thus disclosed my invention, I claim:

1. In a vacuum switch:

(a) an annular vacuumized housing comprising:

- (1) an electrically conductive section;
- (2) an electrically non-conductive section joined to the conductive section; and
- (3) electrically conductive end caps;

(b) an electrically conductive baffle structure mounted within the housing, extending substantially there across adjacent to the joinder of the conductive and non-conductive sections for defining, in spaced relation with the electrically conductive section, an arc chamber for restricting metallic vapor movement from the arc chamber to the electrically nonconductive section;

- (c) a stationary contact assembly mounted to one of the end caps, said stationary contact assembly comprising a stationary rod that has one end thereof extending into the arc chamber;
- (d) a movable contact assembly slidably mounted in the other end cap, said movable contact assembly comprising a rod with one end thereof extending into the arc chamber, adjacent the stationary rod end; and
- (e) a flexible sealing means connected between the movable contact assembly and the other end cap for maintaining a vacuum in the housing for allowing movement therebetween;
- (f) the stationary and the movable contact assemblies being aligned along a common longitudinal axis; at least one of the rods having an axial cavity formed therein offset from the longitudinal axis, for asymmetrically displacing the magnetic fields generated by the contact rods.

2. The combination in accordance with claim 1 wherein:

axial cavities are formed in the adjacent ends of both rods with the cavities being offset from the longitudinal axis and from each other.

3. The combination in accordance with claim 2 wherein the axial cavities are located diametrically from each other.

4. The combination in accordance with claim 1 further comprising:

electrical contacts mounted on the adjacent ends of 30 the rod for engaging each other when the switch is closed.

5. The combination in accordance with claim 4 wherein:

electrical contacts are radially enlarged from the rods 35 and have facing contact surfaces complementary to each other adapted to provide surface to surface contact when the switch is closed.

6. The combination in accordance with claim 4 further comprising gettering material positioned in the axial 40 cavity.

7. The combination in accordance with claim 6 wherein the gettering material is in the form of a post that is mounted in the cavity spaced from the rod.

8. In a vacuum switch encased by an annular housing 45 positioned about the longitudinal axis of the switch:

(a) a stationary contact assembly mounted to the housing comprising a stationary rod extending along the longitudinal axis with an axial cavity formed therein offset from the longitudinal axis;

(b) a movable contact assembly mounted in the hous-

5

10

15

20

ing comprising a movable rod extending along the longitudinal axis opposing and spaced from the stationary rod; and

(c) a flexible sealing means connected between the movable contact assembly and housing for maintaining a vacuum within the housing while permitting movement therebetween.

9. The combination in accordance with claim 8 wherein the movable rod has an axial cavity formed therein offset from the longitudinal axis and diametrically opposite the stationary rod axial cavity.

10. The combination in accordance with claim 9 wherein at least one of the rods has a passageway formed therein communicating with the cavity and the rod exterior.

11. The combination in accordance with claim 10 wherein gettering material is positioned within the cavity.

12. The combination in accordance with claim 11 wherein the gettering material is in the form of a post positioned within the cavity spaced from the rod.

13. The combination in accordance with claim 8 wherein the contact assemblies further comprise electrical contacts mounted to the adjacent ends of the rods, said contacts having facing surfaces complementary to each other and adapted to make surface to surface contact when the switch is closed.

14. The combination in accordance with claim 1 wherein the baffle structure is in the form of a disc that is supported on one of the rods.
